Inventor:

Wallace M. Gray

By C. W. Miles,

Attorney

UNITED STATES PATENT OFFICE.

WALLACE M. GRAY, OF CINCINNATI, OHIO.

LOCOMOTIVE WATER COLUMN.

Application filed March 1, 1920. Serial No. 362,224.

To all whom it may concern:

Be it known that I, WALLACE M. GRAY, a citizen of the United States, residing at Cincinnati, in the county of Hamilton and 5 State of Ohio, have invented certain new and useful Improvements in Locomotive Water Columns, of which the following is a specification.

My invention relates to improvements in 10 locomotive water columns. One of its objects is to provide improved operating means and supporting means therefor to enable an operator on a locomotive tender to adjust and lock the column, and open and 15 close the valve. Another object is to provide improved spout mechanism and supporting means therefor. Another object is to provide an improved spout mechanism having a rigid and renewable sheet metal 20 section and an adjustable and renewable sheet metal section. Another object is to provide an improved combination of spout mechanism and column actuating mechanism and mechanism for jointly supporting 25 the same. Another object is to provide improved spout mechanism having a wide range of adjustment to provide for delivering water to relatively different points. My invention also comprises certain details of 30 form, combination, and arrangement, all of which will be fully set forth in the description of the accompanying drawings, in which:

Fig. 1 is a side elevation of the upper 35 portion of a locomotive water column embodying my improvements.

Fig. 2 is a plan view of the same.

Fig. 3 is a sectional detail of the rigid 40 spout member detached.

The accompanying drawings illustrate the 45 preferred embodiment of my invention in which 14 represents a locomotive water column, which is preferably rotatably adjustable upon a vertical axis by known means and adapted to serve locomotives upon two tracks, and when not in use to be 50 adjusted into position so that the spout and spout supporting mechanism will not overhang either track. The column is adapted 55 to be locked to its adjusted position by known locking means which is actuated to lock and release the column through an end- 60 wise movement of a link or connecting rod 15 which is connected pivotally at its upper

end to a bell-crank lever 16 which is pivotally connected at 17 to a bracket carried rigidly by the elbow section 18 of the water column. Valve rods 20 extending vertically down the sides of the column are pivotally connected at their upper ends to bell-crank 65 levers 21, which are pivotally connected at 22 to rigid projections carried by the elbow section 18 of the column. The vertical movement of the valve rods 20 serves to actuate a valve of known construction at the 70 base of the column where it will be free from danger of freezing, and which valve admits water to the column when opened by lifting the valve rods 20, and cuts off the water supply and drains the column when 75 the valve rods 20 are lowered.

A flange member 24, having a short nipple or spout 25, and of cast metal for instance, is adapted to be bolted to the vertical face of the elbow section 18, and to have renewably connected thereto a relatively long 80 downwardly inclined sheet metal spout member 26, as for instance by telescoping the sheet metal member into the flange 24 to secure a drive fit sufficient to retain the sheet 85 metal member 26 locked to the flange 24 until through injury or corrosion it becomes necessary to renew the section 26. I am thus enabled to provide a spout section 26 of considerable length which is of light 90 weight, and relatively inexpensive, and is readily renewable, thereby providing for an extensive range of adjustment of the adjustable spout section, preserving the balance of the column, and providing for ready renewal or repair in the event of accidental injury, as by leaving the spout overhanging 95 the track in position to be hit by a passing locomotive.

A pair of supporting members 30, as for 100 instance metal angle bars, are rigidly connected to the elbow section 18, and project out over the spout section 26. Rollers 31 are pivotally hung from said supporting members, and an adjustable spout section 33 105 has connected thereto at one end short steel cables 34 which run in grooves in the pulleys 31, and also in grooves in the pulleys 35 pivotally attached to the elbow member 18, said cables being attached at their opposite 110 ends to a weight 36, preferably in the form of a band encircling a vertical section of the water column to enable the column to

act as a guide for the weight. The weight 36 serves as a counterbalance for the adjustable spout section 33 and to enable said spout section to be readily adjusted to a variety of relatively different positions, so as to direct its lower end into the man-hole or filling port of the water tank on the tender of a locomotive, irrespective of the particular type of locomotive, and irrespective of whether the filling port has been accurately positioned along the track beneath the outer end of the spout section 26 of the water column. In Fig. 1 I have illustrated in dotted line to some extent the range of adjustment attainable by the lower end of the adjustable spout section 33. It will be noted also that by reason of the downwardly inclined positions of the spout sections 26 and 33, that as soon as the water supply to the column has been shut off the water will freely drain from said spout sections, and even in freezing weather is not liable to result in an accumulation of ice sufficient to interfere with the operation of the apparatus. Also that such draining of the spout sections is facilitated by the free admission of air between the inner and outer sections at the upper end of the adjustable section, and that this free admission of air at the upper end of the adjustable spout section facilitates the flow of water downwardly and out at the lower end of the adjustable spout section and thus avoids any liability of the water backing up in the adjustable spout section so as to escape at the upper end of the spout section 33, and between said section and the section 26. The counter-weighting of the section 33 enables it to retain any position to which it may be adjusted.

Two valve rods 20, extending along opposite sides of the water column are preferably employed to actuate the valve mechanism without liability of the same to bind or cant, and two bell crank levers 21 pivotally attached by the axle 22 to ears 40 on the elbow section 18 of the column. Pivotally connected to the upper ends of the bell crank levers 21 are two links 41, which at their opposite ends are pivotally connected to a U-shaped hand lever 42, which is pivotally mounted upon a cross-bar 43 carried at the free ends of the supporting members 30. A movement of the hand lever 42 from the full line position Fig. 1, to the dotted line position will serve to lift the valve rods 20 and thereby to open the valve and admit water to the water column, while a movement of the hand lever 42 from the dotted line position to the full line position will lower the valve rods 20 and thereby shut off the water supply to the water column and also drain away any water that may be standing in the water column, to avoid freezing of water therein. A deflector 50

is preferably provided at the lower end of spout section 26 to deflect the water downwardly and avoid direct displacing influence of a water jet on the adjustable spout section 33.

A yoke-shaped hand lever 45 is also pivotally mounted upon the cross-bar 43, and has attached to its forked ends the forked ends of a link 46, the opposite end of which link 46 is pivotally connected to the upper end of the bell-crank lever 16. A movement of the hand lever 45 from its full line position Fig. 1 to about its dotted line position will serve to lift the rod 15 and thereby withdraw a bolt not shown, which locks the column against rotation. The column may then be swung into position with the spout over the track, or into position with the spout parallel with the track as desired, whereupon the hand lever 45 is moved from its dotted line position to its full line position to again lock the column against rotation. Turn-buckle 47 serves to adjust the length of the rod 15, and the turn-buckle 48 serves to adjust the length of the link 46. The hand levers 4 and 45 are thus brought into position where they may be conveniently reached by an operator on the locomotive tender and operated as required in conjunction with the adjustable spout section, thereby effecting a great convenience and a material saving in time, and providing for ready renewal should accident occur.

The downwardly directed supports 30 tend to bring the operating levers more conveniently within the reach of an operator on a locomotive tender. It also together with the relatively long spout section 26 also downwardly directed, and the telescopic spout depending from said supports provides for the increased range of adjustment of the lower end of spout section 33.

Thus the stationary spout section is of relatively greater length, or of substantially the same length as the adjustable spout section, and there is a relatively greater telescopic action, and hence a greater range of adjustment, which is particularly available longitudinally of the track, as for instance so that instead of having to stop a locomotive within a range of four feet to one side or the other of the column, a locomotive may now be stopped and the filling hole reached within a range of nine feet to one side or the other of the column. These results are attained without adding anything to the initial or idle-position projection of the spout, or additional overhanging weight due to the spout and its supporting means. The use of two supporting arms straddling or at opposite sides of the spout, also improves the support and brings the actuating levers lower to the man on the tender.

The apparatus herein illustrated and de-

scribed is capable of considerable modification without departing from the principle of my invention.

What I claim is.

5 1. A locomotive water column comprising a column, a detachably mounted elbow section at the head of said column provided with projections for the attachment of spout supporting arms valve actuating rods and a 10 column locking rod, a pair of spout supporting arms attached rigidly to said elbow and projecting laterally and downwardly therefrom, a sheet metal spout section projecting laterally and downwardly from said elbow 15 section, intermediate of said supporting arms an adjustable sheet metal spout section telescopically adjustable upon and exteriorly of said stationary spout section and counterbalanced relative to said column, and 20 valve actuating means and column locking means mounted upon said supporting arms.

2. A locomotive water column comprising a column, a pair of spout supporting arms projecting laterally and downwardly from 25 the head of the column, a stationary spout section projecting intermediate of and laterally and downwardly from the head of the column beneath and to substantially the same extent as said supporting arms, an adjustable sheet metal spout section telescopically adjustable upon and exteriorly of said stationary spout section, means to counterbalance said adjustable spout section carried by said supporting arms, a valve actuating 30 rod carried by said column and connected by actuating means with an actuating lever mounted at the extended end of said spout supporting arms, and a column locking rod carried by said column and connected by 35 actuating means with an actuating lever mounted at the extended end of said spout supporting arms to enable said actuating levers to be reached and said column to be locked and released and the valve opened 40 and closed from the extended end of said supporting arms by an operator on a locomotive tender.

3. A locomotive water column comprising a column, a detachably mounted elbow section at the head of said column provided with projections for the attachment of spout supporting arms and journal projections to support a valve rod actuating crank shaft and a column locking crank shaft, a pair 45 of spout supporting arms attached rigidly to said elbow and projecting laterally and

downwardly from said elbow, a sheet metal spout section rigidly attached to said elbow and projecting laterally and downwardly from said elbow intermediate of said supporting arms, an adjustable sheet metal spout section supported from said supporting arms and telescopically and laterally adjustable upon and exteriorly of said stationary sheet metal spout section and counterbalanced relative to said column, valve actuated levers pivotally connected to the extended end of said supporting arms, and connecting rods operatively connecting said actuating levers to said valve rod crank 70 shaft and said column locking crank shaft respectively to actuate said valve rod and column locking member from the extended end of said supporting arms.

4. A locomotive water column comprising a column, a pair of spout supporting arms projecting laterally and downwardly from the head of said column, a stationary spout section of light weight projecting intermediate of and laterally and downwardly from the head of column beneath and to substantially the same extent as said supporting arms, a sheet metal spout section telescopically and laterally adjustable upon and exteriorly of said stationary spout section, 80 means to counterbalance said adjustable spout section carried by said supporting arms, a valve actuating rod carried by said column, a valve actuating crank shaft journaled to the head of said column and connected to said valve actuating rod, a valve actuating lever rotatably mounted at the extended end of said spout supporting arms, a connecting rod operatively connecting said valve actuating lever to said valve actuating 85 crank-shaft, a column locking rod carried by said column, a column locking crank shaft journaled to the head of said column and connected to said column locking rod, a column locking actuating lever rotatably 90 mounted at the extended end of said spout supporting arms, and a connecting rod operatively connecting said column locking actuating lever to said column locking crank shaft, to enable said valve rod and column 95 locking rod to be respectively positively actuated in either direction from the tender of a locomotive.

In testimony whereof I have affixed my signature.

WALLACE M. GRAY.
